[57] CLAIM

The ornamental design for an electronic article surveillance antenna for a theft detection system, as shown and described.

DESCRIPTION

FIG. 1 is a perspective view of an electronic article surveillance antenna for a theft detection system showing my new design, with the broken lines showing for illustrative purposes only and forming no part of the claimed design;

FIG. 2 is a front elevational view thereof, with the rear being a mirror image;

FIG. 3 is a left side elevational view thereof, with the right side being a mirror image;

FIG. 4 is a top plan view thereof.

FIG. 4

FIG. 2
